BUCKLE FOR HOLDING RIBBONS

Max Brown, Waterbury, Conn., assignor to The Waterbury Metal Stamping Co., Waterbury, Conn., a corporation of Connecticut

Application March 1, 1950, Serial No. 147,062

2 Claims. (Cl. 24—200)

1

This invention relates to buckles for adjustably holding and connecting ribbons, and more particularly to a buckle of the type which is used in garments such as lingerie, and which is cut or stamped from sheet metal or other suitable material in such a manner as to provide transverse bars forming slots for receiving the ribbons.

One object of this invention is to provide a buckle of the above nature having a lower transverse opening which is so shaped as to avoid bunching of a ribbon which may be threaded therethrough, whereby the ribbon will remain in laterally spread condition in the buckle despite diagonal strains which may occur thereon.

Another object is to provide a buckle of the above nature in which the lower opening extends nearly the full width of the buckle, whereby crowding of the ribbon will be avoided.

Another object is to provide a buckle of the above nature having an oval transverse central slot which is adapted to receive an upper ribbon, and which is particularly adapted to hold in spread condition a ribbon which has been hemmed after being cut from a larger piece of whole fabric and known as a "self-material" ribbon.

A further object is to provide a buckle of the above nature which will be simple in construction, inexpensive to manufacture, easy to install and adjust, compact, ornamental in appearance, and very efficient and durable in use.

With these and other objects in view, there have been illustrated on the accompanying drawing two forms in which the invention may conveniently be embodied in practice.

In the drawing,

Fig. 1 is a perspective view, showing the first form of the improved buckle.

Fig. 2 is a front view showing the buckle as it would appear when used for adjustably connecting a pair of ribbons, the latter being shown partly in section.

Fig. 3 is a front view showing the second form of buckle as it would appear with a pair of ribbons therein.

Referring now to the drawing in which like reference numerals denote corresponding parts throughout the several views, the numeral 10 indicates the first form of buckle which is constituted by a piece of stiff, flat, sheet material so formed as to provide a pair of opposite longitudinal side bars 11, 12 connected by transverse upper and lower intermediate bars 13, 14, and a curved lower end bar 15, the latter bar being in effect a continuation of the lower ends of the side bars 11, 12.

10 The upper ends of the side bars 11, 12 are provided with respective inwardly-extending arms 16, 17 which are disposed in parallel relationship to the upper intermediate bar 13 and which are spaced apart at their inner ends, thus forming an upper transverse slot 18 having a relatively narrow entrance throat 19. The intermediate bars 13, 14 are disposed in spaced relationship and have longitudinally concave 15 facing edges, thus forming a transverse central slot 20 having bulging sides. The slot 20 will be hereinafter referred to as the oval slot, and preferably is so proportioned as to have a central width which is of the order of twice its width at its ends.

20 The side bars 11, 12 are provided with respective inwardly extending and downwardly inclined projections 21, 22 which are spaced apart at their inner ends so as to define with the bar 14 a transverse slot 23 having a central bottom throat 24.

25 The inclined projections 21, 22, taken together with the curved lower end bar 15, define a lower ribbon opening 25 having upwardly inclined end portions 26, 27, located below the projections 21, 22, respectively.

30 In order to provide an abutment which will serve to prevent lateral sliding and bunching of a ribbon in the opening 25, the lower end bar 15 is provided with an upwardly-extending curved central hump 28, the width of which is preferably equal to or greater than the width of the throat 24 so that the central portion of the ribbon opening 25 located above the hump 28 may in effect comprise a portion of the throat 24.

Operation of first form

35 In operation, the buckle 10 may be attached to a loop of ribbon R-1 by first inserting one end of said ribbon through the central oval slot 20, and then bringing said end back through the lower slot 23, after which both ends of the loop may be inserted in the upper slot 18 by passing them together inwardly through the entrance 40 throat 19 with a sidewise motion.

45 Thus, the buckle 10 will be firmly attached to the loop of ribbon R-1, and the shape of the central oval slot 20 will tend to hold said ribbon in a spread condition, inasmuch as the ends of said slot are relatively narrow, and will prevent the ribbon from becoming bunched at either end of the slot.

50 A loop of ribbon R-2 may then be inserted in the lower ribbon opening 25, this operation being facilitated by the presence of the throat 24, which

offers ample room for the insertion of the ribbon. The ribbon R-2 will then be drawn downwardly and spread in the opening 25 so that the edges of said ribbon are disposed in the end portions 26, 27 of said opening.

The buckle 10 and the ribbons R-1, R-2 therein will now be in condition for use, and if a longitudinal strain is exerted upon the ribbons, a central portion of the ribbon R-2 will be stretched over the hump 28, the inclined sides of which will effectively serve to prevent either half of the ribbon R-2 from passing into the opposite half of the opening 25, and thus will prevent diagonal strains from acting adversely upon the proper positions of the ribbons in the buckle.

Second form.

The second form of the invention is embodied in a buckle 29 (Fig. 3) comprising a pair of opposite parallel longitudinal side bars 30, 31, the central portions of which are connected by transverse upper and lower intermediate bars 32, 33, having therebetween an oval slot 34 similar to the slot 20 of the first form. The upper ends of the side bars 30, 31 have inwardly extending arms 35, 36, which define, in connection with the upper intermediate bar 32, an upper transverse slot 37 having a central upper entrance throat 38.

In spaced relationship below the lower intermediate bar 33, the buckle 29 is provided successively with a transverse bar 39 and a curved lower end bar 40, the latter providing in effect a downward continuation of the side bars 30, 31. The bars 39, 40 are spaced from the bar 33 and from each other so as to define a lower transverse slot 41 and a curved lower ribbon opening 42.

By means of this construction, it will be seen that the lower ribbon opening 42 is concave in an upward direction, and comprises upwardly inclined end portions 43, 44, which are defined in part by a pair of humps 45, 46, extending upwardly from the curved end bar 40 adjacent the ends of said opening.

Operation of second form.

The second form of buckle 29 will be used in substantially the same manner as was described above in connection with the buckle 10. Thus, a length of ribbon R-3 will be looped around the lower intermediate bar 33 and extending thence over the upper intermediate bar 32 and under the arms 35, 36.

A loop of ribbon R-4 will then be disposed in the lower ribbon opening 42, opposite edge portions of said ribbon being stretched over the humps 45, 46 so that longitudinal strains which may be exerted upon the ribbon R-4 will hold said ribbon in close engagement with said humps and thus will hold the ribbon in a spread condition in the opening 42.

In view of the foregoing, it will be seen that the present invention provides a buckle which is not only economical to manufacture and easy to assemble with the connecting ribbons, but which will effectively hold the ribbons in a spread condition therein without injury thereto and which will avoid excessive wear thereon, thus avoiding the annoyance or unsightly appearance which occurs when ribbons become bunched or laterally shifted in the connecting buckles.

While there have been disclosed in this specification two forms in which the invention may be

embodied, it is to be understood that these forms are shown for the purpose of illustration only, and that the invention is not to be limited to the specific disclosures, but may be modified and embodied in various other forms without departing from its spirit. In short, the invention includes all modifications and embodiments coming within the scope of the following claims.

Having thus fully described the invention, what is claimed as new, and for which it is desired to secure Letters Patent, is:

1. A buckle for joining the adjacent ends of upper and lower straps, comprising an integral frame having a pair of spaced vertical side bars, said frame having an open top substantially closed by upper bar portions extended inwardly from the upper ends of said side bars, a pair of spaced transverse bars extended between said side bars below said upper bar portions and about which the upper strap is adjustably engaged, a bottom transverse bar joining said side bars and over which the lower strap is passed, inclined lower bar portions extended inwardly and downwardly from said side bars between said bottom bar, and the lower of said spaced transverse bars, said bottom bar having the ends of its upper edge sloping downwardly and inwardly from said side bars, and formed with at least one convex projection extending upwardly and terminating below said inclined bar portions for stretching the lower strap so as to prevent it from shifting relative to the frame.

2. A buckle for joining the ends of upper and lower straps, comprising an integral frame having a pair of spaced vertical side bars, said frame having a pair of spaced transverse bars extended between said side bars and about which the upper strap is adapted to be adjustably engaged, a bottom transverse bar joining said side bars and over which the lower strap is adapted to be passed, inclined lower bar portions extended inwardly and downwardly from said side bars between said bottom bar and the lower of said spaced transverse bars, said bottom bar having the ends of its upper edge sloping downwardly and inwardly from said side bars, and formed with at least one convex projection extending upwardly and terminating below said inclined bar portions for stretching the lower strap so as to prevent it from shifting relative to its frame.

MAX BROWN.
